SIDE WHEELER INFLATED RAFT
Minnie H. Penland, 239 Bonair, La Jolla, Calif., and
Stuart M. Hallum, 3572 Texas, San Diego, Calif.
Filed Aug. 24, 1959, Ser. No. 835,499
4 Claims. (Cl. 115—23)

The present invention relates generally to water craft and more particularly to a side wheeler inflated raft.

The primary object of this invention is to provide an inflated raft having a side wheeler type paddle assembly mounted thereon in which the paddles are angularly positioned to facilitate the use of small yet effective paddles, while providing ample clearance for the hand cranks which operate the paddles.

Another object of this invention is to provide an inflated raft in which the paddles are mounted on a rigid yoke which extends under and around the sides of the raft, so that the paddle action is not affected by flexibility of the raft.

A further object of this invention is to provide an inflated raft in which the paddles can be operated in either direction for forward or reverse motion and also differentially for steering.

Finally, it is an object to provide a side wheeler inflated raft of the aforementioned character which is simple, safe and convenient to operate and which will give generally efficient and durable service.

With these and other objects definitely in view, this invention consists in the novel construction, combination and arrangement of elements and portions, as will be hereinafter fully described in the specification, particularly pointed out in the claims, and illustrated in the drawing which forms a material part of this disclosure, and in which:

FIGURE 1 is a top plan view of the raft;

FIGURE 2 is a sectional view taken on the line 2—2 of FIGURE 1;

FIGURE 3 is a sectional view taken on the line 3—3 of FIGURE 2; and

FIGURE 4 is a sectional view taken on the line 4—4 of FIGURE 2.

Similar characters of reference indicate similar or identical elements and portions throughout the specification and throughout the views of the drawing.

The raft 10 is a multi-cell, plastic inflatable type having a plurality of individual cells 12 separated by internal webs 14. The cells 12 preferably extend transversely although a raft having longitudinal cells may also be used. The raft can be made from individual cells joined together or, for ease of manufacture, may be extruded in one piece as illustrated, the process being well known. The ends of the cells 12 are closed and sealed along common side seams 16 which are reinforced by channelled edge strips 18 which overlap the seams. For convenience, slotted hand grips 20 are secured to or molded into the edge strips 18 to facilitate carrying the raft and to assist in climbing aboard the raft while in the water. To prevent undue flexibility and rolling up of the ends of the raft 10, a flat bottom panel 22, which may also be of plastic material, is bonded to the underside of the raft. For safety purposes, the cells 12 are preferably connected in pairs by internal vents 24 in the webs 14, each pair having an individual inflation valve 26 of conventional type, so that puncture of one cell will not cause the raft to sink.

The paddle assembly is carried on a rigid yoke 30 comprising a flat, elongated bottom plate 32 having upwardly curved bight portions 34 at opposite ends thereof, said bight portions extending into upwardly and inwardly projecting bearing plates 36. The yoke 30 fits transversely around the raft 10 which, when inflated, expands into the bight portions 34 and grips the yoke firmly, as in FIGURE

2

2, with the bearing plates extending angularly inwardly and upwardly over the opposite sides of the raft. If necessary, the yoke 30 can be bonded to the bottom panel 22, although in normal usage the inflation of the raft may be sufficient to hold the yoke in place. For additional rigidity, the yoke is provided with longitudinally extending reinforcing ribs 38 adjacent the edges thereof. On the upper surface of each bearing plate 36 is an elongated bearing 40 formed integrally with or bonded to the bearing plate. The entire yoke 30 may be molded as a unit from plastic material for simplicity and lightness, although other materials and construction can be used if desired. Journalled within the bearings 40 are upper, inner end portions of shafts 42, the extremities of which are provided with hand cranks 44, said shafts having thrust washers 46 fixed there to at the inner or adjacent ends of said bearings. The outer ends of the shafts 42 extend outwardly and downwardly and carry the paddle wheels 48, spacing sleeves 50 being fitted on the shafts between said 10 paddle wheels and the bearings 40 to provide clearance between the paddle wheels and the raft. Each paddle wheel 48 comprises a backing disc 52 having an elongated, axially extending hub 54 into which the shaft 42 fits, the connection being secured by a lock pin 56 through 15 the hub and shaft. Each paddle wheel 48 has a plurality of blades 58 extending radially from the hub 54 and tapering from the full diameter of the backing disc 52 to narrow tip portions 60 at the end of the hub. The tapered blades 58 are more rigid than rectangular blades 20 with unsupported outer corners, yet have ample contact area in the water due to the axially angular mounting of the paddle wheels, the approximate water line indicated in FIGURE 2 serving to illustrate the arrangement. While 25 four paddle blades are illustrated, any suitable number 30 may be used.

The occupant of the raft sits or kneels thereon and can turn the cranks 44 in either direction for forward or reverse motion. By using one paddle wheel 48, or by using both paddle wheels differentially, the raft can be turned 35 and guided and is highly maneuverable, being capable of turning in its own length. The raft can be used to tow swimmers grasping the hand grips 20, and may be used in very shallow water, the paddle wheels being resistant to 40 fouling since the tapered blades 58 will slide off most 45 obstructions. When deflated, the raft 10 can be rolled up and stored inside the yoke 30.

The operation of this invention will be clearly comprehended from a consideration of the foregoing description of the mechanical details thereof, taken in connection 50 with the drawing and the above recited objects. It will be obvious that all said objects are amply achieved by this invention.

It is understood that minor variation from the form of the invention disclosed herein may be made without departure 55 from the spirit and scope of the invention, and that the specification and drawing are to be considered as merely illustrative rather than limiting. For example, the cells 12 may be fabricated from sheets of material bonded directly together along transverse lines at spaced 60 intervals, instead of as indicated in FIGURE 3. By way of further example, considerable modification of the raft, as such, is conceived as possible for use with a paddle wheel assembly substantially as disclosed.

We claim:

1. In combination with an inflatable raft, a paddle wheel assembly, comprising: a rigid yoke extending transversely below and around both sides of said raft; the ends of said yoke having angularly upwardly disposed plate portions extending inwardly and terminating above said 65 raft; bearings fixed on said plate portions; shafts freely rotatably mounted in said bearings and extending angularly outwardly and downwardly from said raft; paddle

wheels mounted on the outer ends of said shafts; each of said paddle wheels having a plurality of tapered blades having their edges converging to narrow tip portions at the outer ends thereof; the inner ends of said shafts having manually operable cranks integral therewith.

2. In combination with an inflatable raft, a paddle wheel assembly, comprising: a rigid yoke extending transversely below and around both sides of said raft; the ends of said yoke having angularly upwardly disposed plate portions extending inwardly and terminating above said raft; bearings fixed on said plate portions; shafts freely rotatably mounted in said bearings and extending angularly outwardly and downwardly from said raft; paddle wheels mounted on the outer ends of said shafts; each of said paddle wheels including a generally flat backing disc, and a plurality of generally radially projecting blades extending from said backing disc and tapering to narrow tip portions at their outer ends; the inner ends of said shafts having manually operable cranks integral therewith.

3. In combination with an inflatable raft, a paddle wheel assembly comprising: a rigid yoke extending transversely below and around opposing sides of said raft, the ends of said yoke terminating above the top of said raft, and extending angularly inwardly and upwardly with respect to said raft; plate portions affixed to said ends of said yoke; bearings mounted on said plate portions; shafts rotatably mounted in said bearings and extending angularly outwardly and downwardly from said

raft; paddle wheels mounted on the outer ends of said shafts, each said paddle wheel having a plurality of tapered blades having their edges converging at the outer ends of said shafts; and manually operable crank handles mounted on the inner ends of said shafts.

4. In combination with an inflatable raft, a paddle wheel assembly comprising: a rigid yoke extending transversely below and around both sides of said raft, the ends of said yoke terminating above the top of said raft and extending inwardly and upwardly with respect to said raft; bearings mounted on said ends; shafts rotatably positioned in said bearings and extending angularly outwardly and downwardly from said raft; paddle wheels, comprising a plurality of tapered blades, mounted on the outer ends of said shafts; and manually operable cranks mounted on the inner ends of said shafts.
